(57) **CLAIM**

The ornamental design for a positive airway pressure delivery console, as shown and described.

DESCRIPTION

FIG. 1 is an exploded front view of a positive airway pressure delivery console in a first embodiment according to our new design;

FIG. 2 is a rear view thereof;

FIG. 3 is a top view thereof;

FIG. 4 is a bottom view thereof;

FIG. 5 is a right side view thereof;

FIG. 6 is a left side view thereof;

FIG. 7 is a sectional view along line 7-7 of FIG. 1; and,

FIG. 8 is a sectional view along line 8-8 of FIG. 1.

In the drawings, the broken lines are for the purpose of illustrating portions of the positive airway pressure delivery console that forms no part of the claimed design.
